UNITED STATES PATENT OFFICE.

HECTOR ALBERT FRANZ, OF HOOD RIVER, OREGON.

ANNUNCIATOR.

1,393,275.

Specification of Letters Patent.

Patented Oct. 11, 1921.

Application filed November 1, 1919. Serial No. 335,063.

To all whom it may concern:

Be it known that I, HECTOR ALBERT FRANZ, a citizen of the United States, residing at Hood River, in the county of Hood River 5 and State of Oregon, have invented certain new and useful Improvements in Annunciators, of which the following is a specification, reference being had to the accompanying drawings.

- 10 This invention relates to certain improvements in annunciators, and has relation more particularly to a device of this general character of a selective alarm type and it is an object of the invention to provide a novel 15 and improved device of this general character embodying a plurality of stations capable of operation one independent of the other, together with means whereby said stations may be caused to work in unison.
- 20 Another object of the invention is to provide a novel and improved device of this general character comprising a plurality of stations each constituting a clock mechanism together with a master clock for operating 25 all of the first named clocks, together with means at each of the stations for setting the same independent of the remainder of the stations to cause a signal or alarm to operate at a predetermined period of time.
- 30 It is also an object of the invention to provide a novel and improved device of this general character including a plurality of stations which may be separately adjusted to operate a signal or alarm at a predetermined 35 period of time, together with means at a main station for causing a portion of said first named stations to operate in unison to afford both a visual signal and an audible signal.
- 40 Furthermore it is an object of the invention to provide a novel and improved device of this general character including a plurality of stations each comprising electrically operated clocks under control of a master 45 clock, and wherein a movable contact contacts with a hand of each of the first named clocks to afford means whereby an electrical circuit may be closed at a predetermined period of time to operate a signal.
- 50 The invention consists in the details of construction and in the combination and arrangement of the several parts of my improved annunciators whereby certain important advantages are attained and the device rendered simpler, less expensive and

otherwise more convenient and advantageous for use, as will be hereinafter more fully set forth.

The novel features of my invention will hereinafter be definitely claimed. 60

In order that my invention may be the better understood, I will now proceed to describe the same with reference to the accompanying drawings, wherein:

Figure 1 is a diagrammatic view illustrating an embodiment of my invention; 65

Fig. 2 is a schematic view of my invention as herein embodied, and in connection with a single station;

Fig. 3 is a view partly in front elevation 70 and partly in section, and of a somewhat diagrammatic character, illustrating one of the stations as herein embodied;

Fig. 4 is a vertical sectional view taken through the device, as illustrated in Fig. 3, 75 and,

Fig. 5 is a fragmentary view in perspective illustrating the mounting for the setting hand, said hand being in a released position.

From the foregoing description, it is 80 thought to be obvious that an annunciator constructed in accordance with my invention is particularly well adapted for use by reason of the convenience and facility with which it may be assembled and operated 85 and it will also be obvious that my invention is susceptible of some change and modification without departing from the principles and spirit thereof and for this reason I do not wish to be understood as limiting myself 90 to the precise arrangement and formation of the several parts herein shown in carrying out my invention in practice except as hereinafter claimed.

My invention as herein disclosed is particularly adapted for use in connection with hotels, schools or the like, and wherein the various rooms are each provided with a station provided with means whereby said station may be adjusted by the occupant of the 100 room to operate an alarm independent of the remainder of the rooms, and wherein, when the occasions require, as in the case of a fire or for any other purpose, the signals at a plurality of stations may be caused to operate 105 at a plurality of stations may be caused to operate, and under which conditions both an audible signal and a visual signal is caused to operate at each station.

As herein embodied a station S is located within each room of a building or at other 110

locations, and each of said stations S constitutes an electrically operated clock under control of a master clock M.

Each of the stations or clocks S comprises 5 an insulating bushing 1, surrounded by the tubular shaft 2 for the hour hand 3. Rotatable around said shaft 2 is a sleeve 4, to which is affixed the minute hand 5. The shaft 2 and sleeve 4 are operatively engaged 10 through the medium of the gearing 6 in a manner whereby the hands 3 and 5 will have requisite movement one with respect to the other around the dial 7. The gearing 6 includes a ratchet wheel 8, with which engages a pawl 9 carried by the armature 10 intermittently operated by the electromagnet 11.

The master clock M in the present embodiment of my invention operates to send 20 out an electrical impulse every minute so that the pawl 9 at each of such periods of time imparts requisite movement through the gearing to the minute hand 5. For this reason the ratchet wheel 8 is provided with 25 sixty teeth.

Each magnet 11 is electrically connected through the medium of the conductors *a* and *b* with a source of electrical energy E, preferably a seven volt battery. Interposed in the 30 conductor *a* is a circuit closer, the movable contact 12 of which making contact once each minute under the influence of the master clock with the stationary contact 14.

Loosely directed through the bushing 1 is 35 a shaft 15 which extends in advance of the dial 7, and said extended portion of the shaft 15 is provided with a setting hand 16. The setting hand 16 in its normal or neutral position is upwardly vertically disposed 40 or positioned at the hour indication 12, and is maintained in such position, or automatically returned thereto through the instrumentality of the coil spring 17, surrounding the inner end portion of the shaft 45 with one end portion of the spring secured to the shaft and the opposite end portion of the spring secured to the corrugated collar or setting 18, positioned inwardly of the bushing 1. The shaft 15 is also provided 50 with a corrugated collar 19, which coats with the collar or setting 18, whereby the setting hand 16 may be held in desired position.

The inner end portion of the shaft 15 engages 55 a button 20 of insulating material, which is carried by the lower end portion of a vertically disposed rock lever 21. Lever 21 is supported intermediate its length at 22, for swinging movement, and the upper 60 end portion has secured thereto a button 23 seated within an opening 24, produced in the upper portion of the casing 25, comprised in the station S. Upon pushing the button 23 inwardly the lever 21 forces the 65 shaft 15 outwardly to free said shaft, and

whereupon the same is rotated through the instrumentality of the spring 17 to return the setting hand 16 to its normal or neutral position and for a purpose which will hereinafter be more particularly referred to.

The outer end portion of the end shaft 15 has suitably affixed thereto a knob 26, whereby means is provided to manually set the hand 16 in accordance with the requirements of practice.

The dial 7 is of a translucent material such as ground or sand glass, and characters 27 are preferably painted upon the front face of the dial, while the inner face of the dial is stained red. Supported inwardly of the dial 7 is a gong or bell 28, having a concave face or surface disposed in a direction toward the dial 7, and which concave face operates as a reflector for the lamp 28^a positioned substantially at the axial center of said bell or gong 28, so that the rays emitted from said lamp will be concentrated upon the dial 7.

The hour hand 3 is of conductive material, as is also shaft 2 to which it is secured, and said shaft 4 is electrically connected through the conductor *c* with the conductor *b* hereinbefore referred to.

The movable contact 12 hereinbefore referred to intermittently also engages a stationary contact 29 and thus sends out over the conductor *d* electrical impulses from the source E. The conductor *d* leads to a contact 30 comprised in a fire key K, and with which engages a movable contact 31 comprised in said key K. Contacts 30 and 31 are normally in engagement, and leading from the contact 31 is a conductor *e* in electrical connection with the setting hand 16 through the shaft 15. Interposed in parallel in the conductor *e* is the bell or gong 28 and the lamp 28^a. The hour hand 3 and the setting hand 16 are provided on their opposed faces with the contact members 32, preferably of platinum, and when said contacts 32 are in engagement, the circuit through the conductor *e* is completed through the conductor *e* leading from the setting hand 16, or more particularly the shaft 15 to the conductor *b*.

In view of this completed circuit, the bell 28 will be caused to intermittently operate by the movable contact 12 during the period the contacts 32 are in engagement one with the other. Should it be desired to discontinue the operating of the bell during this period, it is only necessary to push the button 23 inwardly whereupon the setting hand 16 will return to its normal or neutral position. It is to be stated at this time that when the setting hand 16 is in its normal or neutral position, the contact 32 carried thereby is removed from the path of travel of the contact 32 carried by the hour hand.

The bell 28 in the present embodiment of

my invention, operates with a current of seven volts, whereas the lamp 28^a requires twenty volts. When the button 33 of the fire key F is depressed, the movable contact 31 is disengaged from the stationary contact 30, and the said movable contact is brought into electric engagement with the second stationary contact 34. Leading from the contact 34 is a conductor *b* in connection 10 with an electrical source E', preferably a battery of twenty volts. Also leading from the source E' is a conductor *g*, in electrical connection with the conductor *e'* at a point between the setting hand and the interposed 15 lamp and bell, so that when the button 33 is depressed a current of sufficient voltage will pass through the conductor *e'* to illuminate the lamp 28^a, and to operate the bell 28. By this means indication can be given 20 of a fire, or for some other particular event.

With the button 33 depressed, the bell 28 will continuously ring and the colored rays passing through the dial 7 will direct attention to the fact that the sounding of the 25 bell or alarm is for a particular purpose other than to indicate a specific period of time.

When the button 33 is depressed it also moves a movable contact 31 into contact 30 with a stationary contact 36, and each of these contacts has leading therefrom a conductor *h* comprised in a circuit leading to fire headquarters or other locality, so that at the same time the bell 28 and the lamp 28^a 35 are caused to operate by the depression of the button 33, the circuit through the conductor *h* will also be closed.

While I have hereinbefore particularly described my improved device in connection 40 with a single station, it is to be understood that the various stations will be electrically connected in parallel so that each of said stations may be independently operated under normal conditions, and also 45 operated in unison upon depression of the fire case.

As is particularly disclosed in Fig. 1, the stations S are disclosed as arranged upon three floors of a building and each floor 50 embodies a separate control under a fire key, so that an alarm may be sounded upon one floor independent of the remainder.

From the foregoing description, it is thought to be obvious that an annunciator 55 constructed in accordance with my invention is particularly well adapted for use by reason of the convenience and facility with which it may be assembled and operated, and it will also be obvious that my invention 60 is susceptible of some change and modification without departing from the principles and spirit thereof and for this reason I do not wish to be understood as limiting myself to the precise arrangement and 65 formation of the several parts herein shown

in carrying out my invention in practice except as hereinafter claimed.

I claim:

1. A device of the character described comprising a series of open circuits, a second 70 series of open circuits, a plurality of signal stations interposed in said circuits, means for alternately closing the first mentioned series of circuits at one point and the second mentioned series of circuits, a plurality of 75 signal stations interposed in said circuits, means carried by each station for closing one of the circuits of the first mentioned series at another point, and means for simultaneously closing all of said circuits at 80 all points.

2. A device of the character described comprising a central station, two series of open circuits extending from said station, a plurality of clocks interposed in each of 85 said series, each clock being provided with signal means, means carried by said central station for alternately closing each series of circuits and simultaneously closing each circuit of the series at one point, means carried by each clock for actuating the same when the circuit of the clock is closed at the central station, means carried by the clock mechanism and interposed in another circuit of the series for closing said circuit 95 through the signal means, and a circuit closer interposed in the circuits of one of the series of open circuits for simultaneously closing said circuits through all of the signal means independently of the circuit 100 closing means of the clocks.

3. An electric signal and alarm system comprising a series of open circuits in communication with a central station, secondary 105 clock stations interposed in said circuits, one of said circuits being adapted to regularly energize the actuating means of the clock stations through the medium of the central station, another of said circuits being adapted to energize signal and 110 alarm means carried by the secondary clock stations through the medium of the central station, a circuit closure carried by the central station, said circuit closure being common to all of said circuits for regularly 115 and alternately closing said circuits and means carried by each of the secondary clock stations for closing the second mentioned circuit through the secondary clock stations, a third circuit in communication 120 with the central station and the secondary clock stations and a circuit closure in the third mentioned circuit for simultaneously energizing the signal and alarm means of all of the clocks independently of the remaining circuits.

4. An electric signal and alarm system comprising a series of open circuits in communication with a central station, secondary clock stations interposed in said circuits, one 130

of said circuits being adapted to regularly energize the actuating means of the clocks through the medium of the central station, another of said circuits being adapted to energize signal and alarm means carried by the secondary clock stations through the medium of the central station, a circuit closure carried by the central station, said circuit closure being common to all of said circuits for regularly and alternately closing said circuits and means carried by each of the secondary clock stations for closing the second mentioned circuit through the

secondary clock stations, a third circuit in communication with the central station and 15 the secondary clock stations and a circuit closure in the third mentioned circuit for simultaneously energizing the signal and alarm means of all of the clocks independently of the remaining circuits, through the 20 coöperation of the circuit closure of the central station.

In testimony whereof I hereunto affix my signature.

HECTOR ALBERT FRANZ.
